UNITED STATES PATENT OFFICE.

JOSEPH McMURTRY, OF PITTSBURG, PENNSYLVANIA, ASSIGNOR OF ONE-HALF TO THE PEERLESS LEAD GLASS WORKS, OF SAME PLACE.

DESIGN FOR A LAMP-CHIMNEY.

SPECIFICATION forming part of Design No. 19,838, dated May 13, 1890.

Application filed March 10, 1890. Serial No. 343,410. Term of patent 14 years.

To all whom it may concern:

Be it known that I, JOSEPH McMURTRY, a citizen of the United States, residing at Pittsburgh, in the county of Allegheny and State of Pennsylvania, have invented and produced a new and original Design for Lamp-Chimneys; and I do hereby declare the following to be a full, clear, and exact description of the same, reference being had to the accompanying drawings, forming a part thereof.

My design consists in a lamp-chimney ornamented substantially as represented in the accompanying drawings, in which—

Figure 1 is a side elevation of a lamp-chimney showing the design. Fig. 2 is an enlarged view of a portion thereof. Fig. 3 is a sectional view of the upper portion of a lamp-chimney.

The principal feature of my design is an ornamentation for the top of the chimney; and it consists of a lamp-chimney having a band around the outside of the top of the chimney, consisting of a series of beads.

A indicates the chimney, and B the beaded band. The top of the chimney is plain—*i. e.*, it lies on a horizontal plane as distinguished from a chimney having a scalloped top.

The band B, which surrounds the top, is ornamented with a series of indentations and elevations, forming beads C, lying in a vertical plane and extending from the plain top of the bead around and underneath the said bead, as shown in dotted lines in Fig. 3.

What I claim is—

The design for lamp-chimneys, consisting in a lamp-chimney having a beaded band extending around the outside of the top, the beads of said band extending from the flat top around on the under side of the band, as set forth.

In testimony whereof I affix my signature in presence of two witnesses.

JOSEPH McMURTRY.
